UNITED STATES PATENT OFFICE.

EDWARD L. FORD, OF YOUNGSTOWN, OHIO.

PUDDLING AND APPARATUS THEREFOR.

Application filed March 3, 1921. Serial No. 449,486.

To all whom it may concern:

Be it known that I, EDWARD L. FORD, a citizen of the United States, residing at Youngstown, in the county of Mahoning and 5 State of Ohio, have invented a new and useful Improvement in Puddling and Apparatus Therefor, of which the following is a full, clear, and exact description, reference being had to the accompanying drawings, forming part of this specification, in 10 which—

Figure 1 is a longitudinal section of a kiln embodying my invention;

Figure 2 is a section on the line II—II of 15 Figure 1; and

Figure 3 is an end view partly broken away.

My invention has relation to kilns and has been more particularly designed to provide 20 a kiln for use in connection with puddling furnaces. In the operation of these furnaces it has been found desirable to add scale or cinder in puddling, this scale or cinder being added hot or cold, and to be supplied 25 rapidly in known quantities. My invention provides simple and efficient means whereby this may be accomplished.

The nature of my invention will be best understood by reference to the accompanying 30 drawing, in which I have shown a preferred embodiment thereof, and which will now be described, it being premised, however, that various changes can be made in the details of construction, arrangement and 35 combination of the several parts, without departing from the spirit and scope of my invention as defined in the accompanying claims.

The kiln comprises a long cylinder open 40 at its ends and provided on its inner surface with a helical conveyer. In the construction shown the cylinder consists of an inner lining 2, having a heat insulating jacket 3 surrounding it, the conveyer being in the form 45 of a helical rib 4. Instead, however, of the conveyer being a rib which leaves a central opening axially of the cylinder, it may be a complete helical partition. The cylinder is supported for rotation in any suitable manner, as upon the anti-friction rollers 5, and 50 is rotated by any suitable means, such as the electric motor 6, driving a shaft 7, provided with a pinion 8, which meshes with a gear ring 9 on the exterior of the cylinder. The 55 cylinder may also be provided with anti-thrust means, such as the rollers 10, jour-

naled on a vertical axis and bearing upon opposite faces of one of the bearing rings 11.

12 is a chute into which the open end of the cylinder is arranged to discharge and 60 which, in turn, is arranged to discharge into a puddling furnace which is indicated partly in dotted lines at 13. The cylinder is preferably supported in an inclined position, being inclined downwardly from its 65 receiving to its discharge end. 14 designates a gas burner which produces a heating medium within the cylinder. The receiving end of the cylinder extends into a stack flue 15 which leads to a discharge 70 pipe 16.

The material to be fed to the puddling furnace can be placed in the receiving end of the kiln either by hand or by any suitable feeding means. In the drawing I have 75 shown a supply hopper 17 which is arranged to discharge into a measuring wheel 18, which, in turn, delivers the material to a chute 19, the lower end of which is arranged to discharge into the receiving end of the 80 kiln. The measuring wheel may be rotated by any suitable means, such as the gear connections 20 and 21, with the shaft 7 of the motor 6.

In the operation a definite amount of the 85 material is introduced into the cylinder at each revolution, care being taken that the material in the cylinder shall not extend above the height of the helical conveyer rib. By this means at each revolution of 90 the cylinder, a definite amount of material is delivered at the discharge end, the successive charges being separated by a revolution. When the burner 14 is in operation, the material is heated as it passes through 95 the kiln. By gearing the feeding device to the kiln the feeding operations may be timed with the rotations of the kiln.

As the temperature of the material is never required to be very high, it is preferred 100 that the interior lining of the kiln shall be of metal. This has the advantage of enabling the material to be delivered to the puddling furnace free of any substance which might be broken from the lining, such 105 as pieces of fire brick, and which if incorporated in a puddling ball would ruin such ball.

I claim:

1. The combination with a puddling furnace, of a reagent heating device cooperating 110 with the puddling furnace and ar-

ranged to discharge regulated amounts of reagents into the furnace, substantially as described.

2. The combination with a puddling furnace, of a feeding apparatus cooperating therewith, said apparatus being of the rotary kiln type and arranged to discharge regulated amounts of a reagent into the puddling furnace, substantially as described.
- 10 3. In the manufacture of wrought iron, the step consisting of feeding into the puddle

bath a regulated amount of a reagent and continuing the puddling operation, substantially as described.

4. In the manufacture of wrought iron, 15 the step consisting of feeding a regulated amount of slag cinder into the puddle bath at an intermediate stage of the puddling operation, substantially as described.

In testimony whereof, I have hereunto set 20 my hand.

EDWARD L. FORD.
